Specification for Design.

Patented Feb. 22, 1921.

Application filed December 26, 1917. Serial No. 208,994. Term of patent 3½ years.

To all whom it may concern:

Be it known that I, JAMES H. BAILEY, a citizen of the United States of America, residing in the borough of Manhattan, city, county, and State of New York, have invented a new, original, and ornamental Design for a Savings-Bank, of which the following is a specification, reference being had to the accompanying drawing, forming part thereof, in which—

Fig. 2 a top or plan view of the bank.

I claim—

The ornamental design for a savings bank as shown.

In witness whereof, I have hereunto signed my name.

JAMES H. BAILEY.
